UNITED STATES PATENT OFFICE

HARRY J. LINSE, OF OZONE PARK, NEW YORK, ASSIGNOR TO PRISMATIC PLUG CORPORATION OF AMERICA, OF BROOKLYN, NEW YORK, A CORPORATION OF NEW YORK

IGNITION PLUG

Application filed April 29, 1930. Serial No. 448,231.

This invention relates to electric ignition plugs for use in internal combustion engines for igniting the fuel charge by which it is possible to ascertain the condition of combustion within the engine by observing an extended portion of an insulator body of the ignition plugs, as shown in my Letters Patent No. 1,713,843, dated May 21, 1929, and it is an object of this invention to provide means carried by the insulator body of an ignition plug whereby a uniform spark gap is maintained between the rod and shell electrodes, the rod electrode is secured against longitudinal movement within the insulator, and the light rays of combustion are more readily and intensely deflected from the combustion chamber through the insulator body to the extended end thereof where the light rays are reflected laterally from said end than it has heretofore been possible to accomplish. It is another object of the invention to provide an insulator body of an ignition plug having a bore therethrough with the walls of the bore converging from the end of the insulator body adjacent the spark generating terminals of the plug to compensate for the thermal expansion of the rod electrode and prevent cracking and breakage of the insulator body by the expansion of said electrode. It is another object of the invention to provide a rod electrode of different diameters, the section of smallest diameter comprising the sparking terminal thereof and the section of largest diameter passing through a tapered bore of the insulator body of an ignition plug to dissipate the heat of combustion transmitted from the sparking terminal of the rod electrode to a greater extent throughout the insulator body. The embodiment of the invention comprises a transparent or translucent conical member preferably arranged with prismatic surfaces and secured to the inner end of an insulator body relative to a recess in said end to form a pocket for the engagement of an enlargement of a rod electrode extending through the insulator body and said member, the electrode is arranged with different diameters, the section of largest diameter passing through a tapered bore of the in-

sulator body and the section of the rod of smallest diameter passing through the conical member and constituting the sparking terminal thereof.

In the drawings accompanying and forming a part of this application, Figure 1 is an elevational view of the ignition plug with the shell electrode broken away to show the mounting and arrangement of the insulator body.

Figure 2 is a longitudinal sectional view of the ignition plug.

Figure 3 is a perspective view of the conical member.

Figure 4 is a perspective view of the insulator body; and

Figure 5 is a side elevation of the rod electrode.

In carrying out the invention there is provided a shell electrode 6 of the usual structure having a skirt portion arranged with external screw threads 7 for engaging the ignition plug in the cylinder of an internal combustion engine, and an internal annular shoulder 8 above the skirt portion to form a seat for an annular enlargement 9 intermediate the ends of an insulator body 10 to support the body within the shell electrode, and the insulator body is secured therein by a collar or sleeve 11 engaged within and having threaded connection with the shell electrode with a sealing gasket 12 interposed between the upper portion of the insulator enlargement 9 and said collar, a gasket 12 also being interposed between the lower portion of the enlargement and shoulder 8 to seal the insulator body in the shell to prevent loss of compression in the engine cylinder.

The insulator body 10 is of such a size relative to the shell electrode to compensate for thermal expansion and contraction of the metal of the shell and collar, and comprises a transparent or translucent material, preferably glass, having a portion extended beyond the end of the shell electrode that is engaged by the collar 11, arranged with prismatic surfaces 13 embodying any of the formations illustrated in my aforementioned patent to deflect and diverge the light rays of combustion laterally therefrom. The in-

ulator body has a bore 14 centrally therethrough with an enlarged entrance thereto at the inner end to form a recess at said end, as at 15, with the walls of said bore converging from said recess to the opposite end of the insulator body to compensate for the thermal expansion and contraction of a rod electrode arranged in sections 16, 17 of different diameters, section 16 of largest diameter and of 5 the same diameter for the entire length passes through the bore 14 with the clearance between the wall of the bore and said rod section being the greatest at the juncture of the rod sections 16, 17 and the part of the section 10 16 which becomes the hottest and expands to a greater degree than the upper portion thereof. The free end of the rod section 17 in conjunction with a sparking terminal 18 extending from the skirt portion of the shell 15 electrode constitutes the ignition portion of 20 the plug and to seal the bore 14 and prevent loss of compression in the engine cylinder a gasket 19 is engaged on the rod section 16 between the bottom of the recess 15 and an 25 annular enlargement 20 of the rod electrode at the junction of the rod sections 16, 17, and of a diameter slightly less than the recess 15. The rod section 17 due to the small diameter thereof absorbs the heat of combustion, and 30 the enlarging of the diameter of the section 16 relative to the section 17 will dissipate the heat of combustion preventing deterioration and fusing of the electrical rod electrode with the terminal of an electric conductor connected thereto by impinging the terminal between an electrode securing nut 21 and a binding nut 22 threaded on the upper end of rod section 16, the nut 21 drawing the enlargement 20 against the sealing gasket 19 35 relative to the bore 14 by the aid of washers 23.

The rod electrode section 17 extending from the recess 15 is unsupported for the entire length of the skirt portion of the shell electrode 40 and in this condition is subject to being bent due to thermal expansion or contraction, or excessive vibration whereby the spark gap between the same and the sparking terminal 18 will be varied with the resulting 45 inefficient operation of the plug, the rod section 17 may also absorb an excessive amount of heat which will cause pre-ignition. To overcome these disadvantages the greater part of rod section 17 is supported by a shield 50 comprising a conical member 24 of transparent or translucent material similar to the material of the insulator body 10 having a bore centrally therethrough of slightly larger diameter than the diameter of the rod section 17 to compensate for thermal expansion 55 and contraction of the rod. The cone has a reduced annular portion 25 projecting from the base to engage in the recess 15 and is adapted to extend only partly therein by the 60 35 shoulder formed by said portion 25 and the

body of the member 24 abutting the end of the insulator body 10, to form a pocket to enclose the rod enlargement 20, as shown in Figure 2, and retain the rod electrode within the insulator body without the securing action of the nut 21, and thereby prevent the dropping of the rod electrode into the engine cylinder should the nuts 21, 22 and washers 23 be disengaged from the rod electrode. 70 The conical member is secured to the insulator body by fusing together the material of the conical member and insulator body about the jointure of the same, as indicated in Figure 2, or cementing the member to the insulator body. 75

To collect all possible light rays of combustion and to intensify the deflection of the same longitudinally through the insulator body, the outer surface of the shield or conical member is arranged as a refractive or prismatic surface or surfaces similar to the surface 13 of the insulator body, as shown in Figures 1 and 2. The conical formation of the member also adds to the light ray collectivity thereof. 80

In assembling the ignition plug the rod section 16 is inserted in the bore 14 of the insulator body 10 through the entrance recess 15 with the gasket 19 interposed between the bottom of the recess 15 and the rod enlargement 20, and the enlargement is drawn up against the gasket by engaging the washers 23 and the nut 21 on the extended screw threaded end of the rod section 16 and forcing the same against the top of the insulator body; then the conical member 24 is engaged on the rod section 17 with the reduced portion 25 within the recess 15 and secured to the insulator body by heating the jointure between the conical member and insulator body to fuse the materials together, or a suitable cement may be applied between the same; and then the insulator body is mounted in the shell electrode 6 with the insulator body enlargement 9 engaging the gasket 12 against the shoulder 8 of the shell electrode and the insulator body is secured in the shell electrode by the collar 11 threaded against the gasket 12 interposed between the collar and insulator body enlargement 9. 100

Having thus described my invention, I claim:

1. A translucent insulator body for electric ignition plugs having a bore therethrough of tapered form and arranged with exterior prismatic surfaces adjacent the end with the bore portion of smallest diameter to reflect light rays deflected longitudinally through the body laterally thereof. 110

2. A translucent insulator body for electric ignition plugs having a bore therethrough and arranged with light ray refractive surfaces at both ends of the body, the surfaces at one end deflecting light rays longitudinally through the body to the opposite end where 120 125 130

- the refractive surfaces reflect the light rays laterally therefrom.
3. A translucent insulator body for electric ignition plugs having a bore therethrough with an enlargement intermediate the ends of the body, a portion of the bore tapering from a side of the enlargement to the end of the body, and prismatic surfaces arranged at both ends of the body.
- 10 4. A translucent insulator body for electric ignition plugs having a bore therethrough and arranged with refractive surfaces at both ends, one end being of conical form and arranged to deflect light rays longitudinally through the body and at a predetermined angle to where the refractive surfaces at the opposite end reflect the light rays laterally therefrom.
- 15 5. A translucent insulator body for electric ignition plugs as claimed in claim 3, wherein the portion of the bore extending from the opposite side of the enlargement is of uniform and reduced diameter.
- 20 6. In an insulator body for electric ignition plugs, a translucent body portion having a bore therethrough with an enlargement at one end thereof and arranged with prismatic surfaces at the opposite end, and a translucent conical member having a bore therethrough and mounted in the enlargement with the bore of the body portion.
- 25 7. An insulator body for electric ignition plugs as claimed in claim 6, wherein the conical member is arranged with prismatic surfaces to deflect light rays longitudinally through the member and body portion to the prismatic surfaces of the body portion and reflected laterally from the insulator body by said latter surfaces.
- 30 8. An insulator body for electric ignition plugs as claimed in claim 6, wherein the conical member is secured to the body portion by fusing the material of the member and body portion at the jointure thereof.
- 35 9. An insulator body for electric ignition plugs as claimed in claim 6, wherein the conical member is arranged at the mounting end with a reduced portion adapted to be engaged in the bore enlargement of the body portion and being of a length less than the length of said bore enlargement to form a pocket between the end of said reduced portion of the conical member and the end of the bore enlargement of the body portion.
- 40 10. In an ignition plug, a shell electrode adapted to be releasably mounted in the cylinder of an internal combustion engine, a translucent insulator body mounted in the shell electrode with a portion extending from one end of the shell arranged with prismatic surfaces, said insulator body having a bore therethrough tapering toward the extended portion and having an enlargement of uniform diameter at the end of largest diameter, and
- a rod electrode mounted in the bore of the insulator body of different diameters with the section thereof within the tapered portion of the bore of the insulator body of a uniform diameter substantially equivalent to the smallest diameter of the bore and the portion of larger diameter being of less diameter than the bore enlargement and engaging in said bore enlargement and closing the end of the tapered bore portion.
- 45 11. In an ignition plug, a shell electrode adapted to be removably mounted in the cylinder of an internal combustion engine, a core embodying a translucent insulator body mounted in the shell electrode with an end portion extending from one end of the shell and arranged with prismatic surfaces, said body having a bore therethrough tapering toward the extended end and an enlargement at the end of largest diameter, and a translucent insulator body of conical form arranged with prismatic surfaces and having a bore therethrough united with the first insulator body within the shell electrode and the bore arranged axially with the bore through said first insulator body, and a rod electrode having different diameters extended through the bores of the insulator bodies, the portion extended through the bore of the first insulator body having a uniform diameter substantially equal to the smallest diameter of said bore and the portion engaging the enlargement of said bore and the bore of the second insulator body being of less diameter than said enlargement and bore, and said electrode having the sparking terminal adjacent the conical insulator body.
